UNITED STATES PATENT OFFICE.

JOSEPH GERARD, OF GAINESVILLE, TEXAS.

TRAIN SIGNALING SYSTEM.

No. 823,114.

Specification of Letters Patent.

Patented June 12, 1906.

Application filed July 31, 1903. Serial No. 167,792.

To all whom it may concern:

Be it known that I, JOSEPH GERARD, a citizen of the United States, residing at Gainesville, in the county of Cooke and State of Texas, have invented a new and useful Train Signaling System, of which the following is a specification.

This invention relates to train signaling systems.

One object of the invention is to provide a signaling mechanism for use in connection with trains having automatic air-brakes of the Westinghouse or other type that will immediately notify the engineer, by means of a suitable alarm, if the system is not in proper order, as by the stoppage of the air-pump or the presence of a closed angle-cock on either the train-pipe or the signal-pipe.

A further object of the invention is to provide an air-brake and signaling system in which there is a complete circuit from the engine through to the rear of the train and thence returning to the engine, so that in the event of the closed angle-cock in any position the engineer may apply the brakes through one pipe up to the closing-cock and thence in the opposite direction through the other pipe to the cock.

A further object of the invention is to provide a signaling system which will set into operation an automatic sounding alarm on alteration of the pressure.

A still further object of the invention is to provide a novel form of signaling mechanism by which the train crew may signal the engineer without causing material reduction of the pressure in the signal-pipe and in which the air contained in the signal-pipe is not used direct for actuating the whistle or similar alarm on the engine.

A still further object of the invention is to provide a signaling mechanism in which an auxiliary reservoir is supplied with air from the signal-pipe and is utilized for sounding the whistle on the reduction of pressure in the signal-pipe.

A still further object of the invention is to provide an improved form of signal-valve for which the necessity of a separate passage from the signal-pipe to the whistle connection is avoided, so as to insure proper operation of the diaphragm at all times.

A still further object of the invention is to provide an adjustable governing device which may be set to operate at any pressure and

sound an alarm during the increase or decrease of pressure beyond a given point.

A still further and important object of the invention is to provide a brake and signaling system in which the reducing-valve is arranged at the rear end of the train and serves as a connection between the train-pipe and the signal-pipe.

With these and other objects in view, as will more fully hereinafter appear, the invention consists in the novel construction and arrangement of parts herein described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is an elevation, partly in the nature of a diagram, of a train signaling system constructed and arranged in accordance with the invention. Fig. 2 is a sectional elevation of the more important members of the system, including the signal-valve and the governor. Fig. 3 is a sectional elevation of an ordinary form of reducing-valve for connecting the train-pipe to the signaling-pipe. Fig. 4 is a fragmentary view of a portion of the structure shown in Fig. 2, the valve being illustrated in a different position. Figs. 5, 6, and 7 are views of details more specifically referred to hereinafter.

Similar numerals of reference are employed to indicate corresponding parts throughout the several figures of the drawings.

In carrying out the present invention the equalizing-valve is removed from its place on the engine and is disposed at the rear end of the train, forming a part of the train crew's equipment and being placed in position by the crew on taking charge of the train. The train-pipe is arranged in the ordinary manner and coupled through to the end of the train, its rear end being connected to the reservoir end of the reducing-valve 2, which may be of the usual construction, and the ordinary signal-pipe is connected to the signal-pipe end of the valve, so that there is formed a continuous air-line from the engine through the train-pipe to the rear end of the train and thence returning to the engine by the signal-pipe. The reducing-valve is set in the usual manner to reduce to about forty-five pounds.

On the engine is placed a signal-valve 3 in the form of a cup-shaped casing having a removable head 4, and the lower end of the casing communicates by a pipe 5 with the usual signal-whistle or other alarm 6 in the cab. 5

Between the cap and main body of the signal-valve is placed a diaphragm 7, connected to the valve-stem 8, carrying a valve that governs the flow of air under pressure to the whistle, such air being supplied from an auxiliary reservoir 9, which in practice will be of about the same size as an ordinary equalizing-reservoir and connected to the lower portion of the signal-valve by a pipe 10. The 10 signal-pipe 1 is connected by a branch pipe 11 to the upper portion of the signal-valve, and the pressure of air in the signal-pipe serves to depress the diaphragm and maintain the valve in closed position. When this 15 pressure is reduced, as by the opening of the ordinary conductor's valve, the diaphragm will raise and allow air to pass from the auxiliary reservoir through pipe 5 to the whistle 6. 20

The upper portion of the signal-valve is 25 connected to the pipe 10 by means of a branch pipe 12, having a check-valve 13 opening in the direction of the pipe 10, and through this pipe air is supplied to the auxiliary reservoir until its pressure is equal to 30 that of the pressure in the signal-pipe. When the signal-pipe pressure is reduced, the valve will automatically close in order to prevent the air from passing through the auxiliary reservoir to the upper end of the signal-valve. 35

At a convenient point on the engine is arranged a governor 14 in the form of a two-part casing having suitable booting-flanges, or it may be formed by an integral casing, if desired. This casing is separated into two 40 chambers by a piston 15, having a suitable stem 16 surrounded by a helical compression-spring 17, the stress of which may be adjusted by a nut 18, extending through the end of the casing, and in the spring-chamber is a 45 vent 19 to permit the free passage of air. The chamber on the opposite side of the piston is connected by a pipe 20 to the signal-pipe, said pipe 20 having a check-valve 21 with openings through the signal-pipe. In the 50 lower portion of the casing is a port 22, communicating with the upper portion of the signal-valve by means of a pipe 23, said pipe being provided with a check-valve 24, which opens in the direction of the port 22. The 55 casing is further provided with a second port 25, connected by a pipe 26 to an automatic signal 27, which may be in the form of a whistle, and immediately below the signal 27 is placed a valve 28, normally held in open position by means of a suitable spring. 60

In the pressure-chamber of the governor is a V-valve 30, connected to and movable with the piston, said valve having a port 31, which may be adjusted to position to place the 65 ports 22 and 25 in communication with each

other, and when this occurs air will pass from the top of the signal-valve through pipe 23, port 20, valve-port 31, port 25, to pipe 26, and thus sound the alarm 27. Under normal conditions, however, the valve will be moved 70 to close the port 22, so that the signal 27 will not be sounded until the pressure of the signal-pipe is reduced to such an extent as to allow spring 17 to move the valve and again open communication between the ports 22 75 and 25. 75

In the operation of a mechanism of this character the train-pipe and signal-pipe are coupled together through the reducing-valve at the rear end of the train, and air under 80 suitable pressure (about forty-five pounds) flows through the pipe 11 to the upper end of the signal-valve and passes through pipes 12 and 10 to the auxiliary reservoir 9 until the pressure in the reservoir is equal to that in 85 the signal-pipe. At the same time the air will force the diaphragm 7 down and maintain the valve in closed position, so that the whistle 6 cannot be sounded until the signal-pipe pressure is reduced. Air will also flow 90 through the pipe 20 to the pressure-chamber and will force the piston or diaphragm 15 outward, and during the first part of this operation when the pump is first started the ports 22 and 25 will be placed in communication 95 with each other and air will pass through pipe 23 and through these ports to the pipe 26, sounding an alarm 27. The alarm 27 continues to sound during all of the outward movement of the piston or diaphragm 15 until the valve is moved to such position as to close port 22, and during this interval the engineer is informed that the pressure in the signal-pipe and the auxiliary reservoir 9 is increased to a predetermined extent to which 100 the governor-spring 17 is set, and thereafter any increased pressure will not act to cause the sounding of alarm 27, nor will the alarm be sounded except during the short interval that 105 the pressure is increased between two points, 110 as from thirty-five to forty pounds, the valve closing in one direction at thirty-five pounds pressure and at forty pounds pressure in the 110 opposite direction. 110

In starting the apparatus into operation 115 the air is forced through the train-pipe from the engine in the usual manner, and as both the train-pipe and the signal-pipe are provided with pressure-gages in the cab the engineer can readily tell whether the parts are 120 in proper working order. If the train-pipe gage only is moving, he will note that the angle-cock on leaving the train-pipe or signal-pipe is closed, or if the pressure is not increasing on either gage he will note that the pump 125 is stopped. As soon as the auxiliary reservoirs of the brake system are filled and the pressure in the signal-pipe increases he will be informed by the first sounding of the alarm-whistle 27 that the pressure is at about 130

thirty-five pounds, and he may then hold the normally open valve 28 in closed position until the pressure increases to forty pounds or more, during which interval the valve 30 moves to closed position.

Should it not be discovered that the angle-cock is closed or should the cock be accidentally closed or other stoppage occur from accident while running, the engineer can manipulate all of the air-brakes by the train-pipe down to the point where the pipe is closed and in the opposite direction can operate the remaining brakes to the rear of the closure by reducing the pressure of the signal-pipe and through reducing-valve the pressure at the rear end of the train-pipe.

While the degree of pressure in the signal-pipe may be altered, it is found in practice that by having a pressure of forty-five pounds and by setting the governor-spring for a pressure of forty pounds the signal-pipe pressure may be reduced and the signal 6 sounded for a number of successive times without reducing the pressure of the piston or diaphragm 15 to such an extent as to allow valve 30 to open and sound the alarm-whistle 27.

While the diaphragm has been described as employed in the signal-valve and a piston for the second valve, it is to be understood 30 that either pistons or diaphragms may be employed in either case.

On the train-pipe side of the reducing-valve is a valve-seat 40, against which seats a spring-pressed valve 41, having a leakage-opening 42, through which a small volume of air may pass from the train-pipe through the signal-pipe. When the air-hose is first coupled, the valve permits prompt charging of the signal-line, and the piston of the governor is quickly moved to running position 40 and retained there until the pressure falls from any cause, when the piston moves in the opposite direction and the valve is opened to allow air to pass through the whistle. The 45 valve 41 is held closed by a spring 44, exerting about five pounds pressure, and normally will not open unless there is considerable reduction of pressure in the signal-pipe, and the air cannot leak through the opening 50 42 in time.

Freight-cars are not usually equipped with signal-pipes; but with the use of the apparatus forming the subject of the present invention the train-pipe may be utilized by the conductor to sound a signal-whistle in the cab. On reference to Fig. 5 it will be seen that the signal-hose and train-pipe hose are coupled together at the pilot of the engine, and the conductor by the usual conductor's valve at the 60 caboose may reduce the train-pipe pressure five or six ounces, and this will permit the sounding of the alarm without setting the brakes; inasmuch as the triple valve of the brake system will not respond to a reduction 65 of this kind. Fig. 5 also shows the applica-

tion of a portion of the device in the caboose, the air-reservoir and governor alone being used and being connected in the manner shown in Fig. 7. In this case both the governor and the reservoir 9 are connected to the 70 train-pipe, and the pressure of the spring 17 is so regulated that the whistle would not be sounded on a service application of the brakes; but in the event of a closed angle-cock or the failure of the pump the pressure 75 would be reduced to such an extent as to permit the sounding of the alarm, and thus notify the conductor and rear brakeman of the fact.

In order to prevent the operation of the 80 signal-valve on a freight-train when the engineer is applying brakes, I employ a cut-out cock 46 on the pipe 10, leading from the reservoir 9, and said cock is connected to the engineer's brake-valve by a link 47, so that 85 when a valve is moved for a service or emergency stop the cock 46 will be closed and both signal-whistles cut out, so that neither can sound while the brakes are being applied.

Having thus described the invention, what 90 is claimed is—

1. In an apparatus of the character described, a train-pipe extending from the engine to the rear end of the train, a signal-pipe extending from the rear end of the train to the 95 engine, and a reducing-valve disposed at the rear end of the train and connecting the two pipes, the connection through the reducing-valve serving to permit constant communication between the train and signal-pipe and the automatic restoration of air-pressure in the latter after each signaling operation.

2. In apparatus of the class described, train and signal pipes extending throughout the length of the train, and a detachable reducing-valve forming a part of the equipment of the train crew, said valve having an air-hose coupling connection for connection with the air-hose couplings of both train and signal pipes at the end of the train, the connection through the reducing-valve serving to permit constant communication between the train and signal pipes, and the automatic restoration of air-pressure in the latter after 105 each signaling operation.

3. In a train signaling mechanism, the separate train and signal pipes, and a reducing-valve arranged remote from the engineer's position and forming a connection between the two pipes, said reducing-valve comprising means for permitting constant communication between said pipes and the automatic restoration of air-pressure in the signal-pipe 110 after each signaling operation.

4. In a signaling mechanism, the combination with the train signal-pipe of an air-brake system, a pressure-operated signal including a valved casing connected with the signal-pipe, and an auxiliary governing and signaling device having a pressure-supply 125 130

connection with the signal-pipe through the casing of the pressure-operated signal device.

5. In a train signaling mechanism, the combination with the train signal-pipe of an air-brake system, of a pressure-operated signal device including a valve-casing connected with the train signal-pipe, and an auxiliary governing and signaling device having a pressure-controlled valve, said auxiliary device 10 having direct connection with the train signal-pipe, and also a separate pressure-supply connection with said pipe through the casing of said pressure-operated signal device.

6. In a signaling mechanism, the combination with the train signal-pipe of an air-brake system, a signal-valve casing having a diaphragm therein exposed directly to the signal-pipe pressure, a signal-whistle, an auxiliary reservoir supplied by the signal-pipe 15 and communicating with the signal-whistle, a valve carried by said diaphragm and controlling the connection between the auxiliary reservoir and the signal-whistle, and an auxiliary governing and signaling device including 20 an auxiliary alarm, a valve-casing having an indirect connection with the signal-pipe through said signal-valve casing, and a piston-controlled valve operating to place the 25

auxiliary alarm in and out of communication with its source of pressure-supply.

7. In a signaling mechanism, the combination with a train signal-pipe of an air-brake system, of a signal-valve casing provided with a valve-seat, a diaphragm working in the casing and carrying a valve coöperating with said seat, an auxiliary reservoir in communication with said casing at one side of the valve-seat, a signal-whistle having a pipe communicating with the casing at the other side of said valve-seat, a pipe connection between the train signal-pipe and the casing at one side of the piston member therein, a similar connection between the casing at the same side of the piston member therein and the auxiliary reservoir, and an auxiliary governing and signaling device having an indirect pressure-supply connection with the train signal-pipe through said signal-valve casing.

In testimony that I claim the foregoing as my own I have hereto affixed my signature 45 in the presence of two witnesses.

JOSEPH GERARD.
